ABSTRACT: This invention relates to a pair of devices for use on a table top or game board. They consist of bottom plates to be positioned on a table top, vertical boards extending from the bottom plates, clamping means to attach the boards to the table top and baskets supported by the vertical boards. The clamping means are such as to allow no relative movement between the pair of devices positioned opposite each other mounted on a table top. These devices may be used in play with balls, darts, or the like.

GAME BOARDS WITH CLAMPING MEANS

My invention relates to game boards, and more particularly to an accessory adaptable for use in games of varied types.

The object of my invention is to provide a board, of varied form, shape, or contour, constructed in a manner to permit attachment to a table, or plate, without mechanical training, or special equipment.

Still another object is to provide a device of the character described, that may be used with varied units, such as tennis balls, dart balls, or the like.

A further object of my invention is to provide a device designed for removing parts and features, and replacing them for identifying the game to be played.

It is manifest to anyone, that games of diversified nature are attractive to most people, and a single unit that may be employed for use with numerous rules and regulations is a novel device.

The device is economical to manufacture and easy to apply to any conventional plate, or table. Other and further objects of my invention will become more apparent as the description proceeds when taken in conjunction with the drawings, in which:

FIG. 1, is a perspective view of the assembled device having the back board angularly disposed;

FIG. 2 is a perspective view of a modified structure with the backboard radial in contour;

FIG. 3, is a top, or plan view of the device shown in FIG. 1, applied to the sides of a table, or the like;

FIG. 4, is a similar view of the device shown in FIG. 2, applied to the ends of the table, or the like;

FIG. 5, is a perspective view of a suggested serving board, which may be applied onto the surface of the table as shown in FIG. 4;

FIG. 6, is a fragmentary cross-sectional view of the device, showing a conventional means for clamping it to the board or surface;

FIG. 7, is another cross-sectional view showing another clamping means; and

FIG. 8, is a fragmentary top view of the device shown in FIG. 1, with additional side plates forming a part of the angular backboard.

Similar characters of reference indicate corresponding parts and features constituting the device, and referring now to the same, the character 10 shows a vertical board extending upward. This board may be of any shape, or contour and is shown angular in FIG. 1, and radially disposed in FIG. 2. It may be constructed of any type of material, such as wood, plastic, cardboard, or the like.

There is a bottom plate section 11 conforming with the shape of the board 10, and an extension plate 12 extending outward from the bottom plate 11. Both plates 11 and 12 are shown equipped with apertures 13 to conform in number with the requirements of the game to be played.

The extension plate 12 is shown equipped with a pair of clamping members 14, which may be of any conventional design, and shown provided with screws 15 to be manipulated manually when the assembled device is attached to a plate 16, which plate may be in the form of a table, or the like.

The vertical board 10, is shown supporting a net, or basket 17, which may be removably attached at 18, making it easy to remove it if the net 17 is not required in the game to be played.

In FIG. 8, I show the board 10 equipped with outwardly extending plates 19, which are oppositely disposed and form a part of the vertical plate 10.

If desired a removable unit shown as 20 in FIG. 5, may be placed onto the table 16 as shown in FIG. 4, as part of the game to be played.

By referring to FIGS 3 and 4, it will be noted that the entire unit generally shown as 21, may be placed at the side of the table 16 as shown in FIG. 3, or at the ends of the table 16 as shown in FIG. 4, depending on the type of game to be played, and its arrangement.

A modified arrangement of clamping the units 21 onto the table 16, is shown in FIG. 7, where the units 22 form a part of the unit 21 and are equipped with longitudinal arms 23 engaging a tubular sliding member 24, and supported by the screws 25.

From the above description it will become manifest to anyone, that the device covered by my invention, is a separate unit that may be constructed and applied in a very simple manner. In as much as games vary to a great extent, various game arrangements with various gaming accessories such as the nets 17 or apertures 13 may be formed to employ the unit 21 in various ways. The device covered by my invention thus fulfills objects of my invention.

Although I have shown a specific construction and arrangement of the parts and features covered by my invention, I am fully cognizant of the fact that many changes may be made in the parts and features, without effecting the performance of the device, and I reserve the rights to make such changes as I may deem convenient or necessary, without departing from the spirit of my invention, or the scope of the appended claims.

Having thus described my invention, what I claim and desire to secure by letters patent in the United States is:

1. A pair of game board devices that can be applied to a table, each device including:

a bottom plate that is positionable on a table top, a vertical board extending from said bottom plate, a game accessory means on said vertical board and said bottom plate,

clamp means for associating said device to a table top with said bottom plate being held contiguously with said table top, wherein said clamp means is formed to engage a table and said clamp means include a means for holding both clamping means together, said clamping means having longitudinal arms, and said means for holding both clamping means together includes a tubular sliding member that is formed to receive both longitudinal arms.

2. A game board device, as defined in claim 1, wherein said bottom plate has apertures formed therein for purposes of playing certain games.

3. A game board device, as defined in claim 1, wherein said vertical board has a basket attached thereto.

4. The devices of claim 1, wherein each vertical board comprises a pair of walls set at a right angle with a basket attached thereto.

5. The devices of claim 4, wherein each vertical pair of walls includes a pair of outwardly extending plates on opposite sides of said vertical walls.

6. The devices of claim 1, wherein said vertical board includes a structure having a radial contour.
